UNITED STATES PATENT OFFICE.

GEORGE R. OSBORN AND BENJAMIN A. DRAYTON, OF NEW YORK, N. Y.

DESIGN FOR A BIRD-CAGE.

Specification forming part of Design No. 5,255, dated September 5, 1871.

To all whom it may concern:

Be it known that we, GEORGE R. OSBORN and BENJAMIN A. DRAYTON, of the city, county, and State of New York, have jointly invented and produced a new and original Design for a Bird-Cage, of which the following is a specification:

The nature of our design is the use of crimped wires in the dome of the cage, as shown in the accompanying photograph, giving a peculiar and distinctive character and appearance to the architecture of bird-cages; in short, creates a new class, which can be varied but little in its general effect and distinctive feature.

Although the general form of the dome may be varied from a simple hemispherical to a reverse or a complex form, and the crimp of the wires

may be on a greater or lesser angle, in the ratchet form, or a series of half circles, or an alternating or compounding of these forms, still the general appearance and distinctive character would remain the same, forming as a whole a corrugated dome or roof, with a varying form and effect of light and shade peculiar and pleasing to the eye.

We claim—

The use of crimped wires as a new style of ornamentation for the upper section, dome, or roof of a bird-cage, as herein specified and shown.

GEORGE R. OSBORN,
BENJ. A. DRAYTON.

Witnesses:

ALVAN DRAYTON,
C. MORTIMER OSBORN.
